UNITED STATES PATENT OFFICE.

LYMAN O. HIGLEY, OF WILLISTON, NORTH DAKOTA.

AUTOMATIC DOOR-ACTUATING HINGE.

1,300,267.

Specification of Letters Patent. Patented Apr. 15, 1919.

Application filed February 1, 1918. Serial No. 214,822.

To all whom it may concern:

Be it known that I, LYMAN O. HIGLEY, a citizen of the United States, residing at Williston, in the county of Williams and 5 State of North Dakota, have invented certain new and useful Improvements in Automatic Door-Actuating Hinges; and I do hereby declare the following to be a full, clear, and exact description of the invention, such as will enable others skilled in 10 the art to which it appertains to make and use the same.

My invention has for its object to provide an improved and highly efficient actuating 15 device for swinging doors and gates, and to such ends generally stated, the invention consists of the novel devices and combinations of devices hereinafter described and defined in the claims.

20 The chief novelty of the invention is in an improved hinge structure whereby the door or gate may be caused to automatically swing from a closed to an open position, or conversely, according to the setting of a so-called fulcrum shifter of the hinge. This movement of the so-called fulcrum shifter may be accomplished in various different ways, to wit, either by manually operated 25 or by vehicle operated devices.

30 The invention is well adapted for use on garage doors, and in such application, there would preferably be a vehicle actuated device outside of the garage and a manually operated device, such as a lever within the 35 garage for controlling the action of the hinge. For farm gates, for example, vehicle operated devices would preferably be provided, one within and one without the yard.

In the drawings, I have illustrated my invention as applied to a garage door, and 40 for brevity of statement in the following specification and in the claims, will refer to the device as applied to a door, but it will, of course be understood that the term 45 "door" as thus used, must be taken in a broad sense to include a gate or similar swinging device for opening and closing a passageway.

In the drawings, like characters indicate 50 like parts throughout the several views.

Referring to the drawings,

Figure 1 is a front elevation of the garage illustrating my invention as applied thereto;

55 Fig. 2 is a view partly in elevation and partly in vertical section and with some

parts broken away, showing the garage and the door actuating mechanism;

Fig. 3 is a plan view of the parts shown in Fig. 2, some of the said parts being indicated in diagram;

Fig. 4 is a detail view in elevation of the vehicle actuated crank of the mechanism;

Fig. 5 is a vertical section on the line 5—5 of Fig. 4;

Fig. 6 is an enlarged view in front elevation of the lower hinge structure and showing also a portion of the door;

Fig. 7 is a horizontal section on the line 7—7 of Figs. 2 and 6, some parts being broken away;

Fig. 8 is a view corresponding to Fig. 7, but showing the door swung nearly to an open position; and

Fig. 9 is a vertical section on the line 9—9 of Fig. 7.

The garage is indicated by the numeral 10 and its swinging door by the numeral 11. In its hinged edge this door is connected to the door frame of the door opening 80 by a hinge that will permit both swinging and a slight lateral oscillatory movement of the door. As shown, this hinge comprises a bearing 12 fixed on the door frame, and a vertical hinge pin 13 on the door, the said 85 pin being passed loosely through a perforation in said bearing and having a nut or similar device 14 secured to its upper end above said bearing. This nut 14 should be keyed, or otherwise secured against rotation 90 on the pin 13 so that it will carry the gate of the door. At its swinging edge the door is shown as provided with an ordinary latch 15 which, of course, constitutes no part of my invention.

The lower hinge corner of the door is shown as provided with a notch at 16, and secured to the door just above this notch is a pair of angle brackets 17, to the out-turned ends of which is bolted, riveted, or otherwise rigidly secured a so-called hinge head 18 shown as in the form of a square bar that extends at a slight angle to the door and projects on both sides thereof. At points equidistant from the opposite faces 105 of the door, this hinge head 18 is provided with depending fulcrum pins 19 for an important purpose. Directly underlying the head 18 but spaced with clearance therefrom and located in the notch 16 when the door is closed, is a so-called fulcrum shifter 110 which constitutes one of the important ele-

ments of the lower hinge. This fulcrum shifter 20, as shown, is of approximately triangular form, at two of its corners is formed with pin or fulcrum seats 21 and at 5 its third corner is pivotally mounted on a stud 22 projecting upward from a floor plate 23 that is suitably anchored to the floor or the sill of the door opening. The axis of the stud 22 is preferably vertically 10 alined with the axis of the upper hinge pin 13.

As the door is hung on the upper hinge, its weight will, of course, force the lower portion of the door toward the fulcrum 15 seats 21 of the fulcrum shifter 20, and hence, will tend to cause the two fulcrum pins 19 always to engage with the said two fulcrum seats. Hence, it follows that when the fulcrum shifter 20 is in the position shown in 20 Fig. 7, the door, in pressing its pins 19 into the seats 21, will tend to hold the door in such closed position. It also follows that when the fulcrum shifter 20 is moved into the position shown in Fig. 8, the outer side 25 seat 21 will be moved from the outer side pin 19 and the pressure from the door is then resisted by the engagement of the inner side pin 19 with the inner side fulcrum seat 21, throws the line of force of the weight of 30 the door outward of the engaged pin 19 and seat 21 and will cause the door to swing from its closed toward its open position until it has again effected the engagement of both of the pins 19 with the coöperating 35 seats 21. The door will then be in an open position. In Fig. 8, the door is indicated as moving toward its open position but not yet having reached its extreme open position.

40 When the fulcrum shifter 20 is moved from the position thereof shown in Fig. 8, back into the position thereof shown in Fig. 7, a reverse action from that just described will take place, to wit, the inside seat 21 will be removed from the inside pin 19 and the pressure from the door will then be resisted only by engagement of the outside pin 19 by the outside seat 21, and this will cause the door to be automatically swung 45 from its open back to its closed position.

For imparting the above noted oscillatory movements to the fulcrum shifter 20, I preferably provide a long bar or rod 24 which is pivotally connected to a lug 25 projected from one corner of the said fulcrum shifter. In the drawings I have illustrated two different devices for imparting endwise movements to the actuating bar or rod 24 within the garage. A lever 26 is pivoted to a 55 bracket 27 and the lower end of this lever is shown as pivotally connected to the inner end of the said actuating rod. This lever may be used to set the fulcrum shifter in a 60 position to close the garage door after a machine has been driven into the garage.

In Figs. 2 and 3, the numeral 28 indicates a post which affords a stop for limiting the opening swinging movement of the door, to a position approximately at ninety degrees to its closed position.

For operating the door by the passage of an automobile to or from the garage, I provide a crank 29 journaled in suitable bearings such as afforded by a rectangular box 30 set into the driveway in suitable position 70 to be run over by the wheels of the machine. At one end, the crank 29 is provided with an upwardly projected arm 31 and a depending arm 32. A weight 33 is hung from the arm 32 and yieldingly holds the crank 75 29 projecting vertically upward. The crank arm 31 is provided with a wrist pin 31^a that works in the slotted end 24^a of the actuating rod 24.

If the garage is closed and a machine 80 approaching the garage runs over the crank 29, the wrist pin 31^a will be at the inner extremity of the slot 24^a and the movement of the crank toward the garage under the pressure of the wheel will move the actuating 85 rod 24 in a direction toward the garage, thereby setting the fulcrum shifter into a position to cause the garage door to swing open. If on the other hand, the machine is moved in a direction away from the garage, 90 while the garage door is open, the crank 29 will be pressed in a direction away from the garage door and actuating rod, being moved in the same direction, will set the fulcrum shifter crank in a position to cause the door 95 to swing from its open to its closed position.

It is highly desirable that provision be made whereby it is impossible to shift the actuating rod 24 from the one extreme to the other extreme position until after the 100 door has made the complete swinging movement from its open to its closed position, or from its closed to its open position. This I accomplish by simple means which is preferably as follows:

The numeral 34 indicates a lock dog that is pivoted to the projecting arms of a bracket 35 rigidly secured on the floor plate 23. This dog 34 has a projecting lock lug 35^a that is engageable with the opposite ends 110 of a lock bar 36 that is rigidly secured to and extends longitudinally of the actuating rod 24. The opposite ends of this bar 36 afford lock shoulders 37 and 38 for coöperation with the lock lug 35^a. These lock 115 shoulders 37 and 38 are so spaced that the said lock shoulder 37 will be positioned just inward of the lock lug 35^a when the fulcrum shifter 20 is set in a position to cause the door to swing from a closed to its open position (see Fig. 8) and the said inner shoulder 38 will stand just outward of said lock lug 35^a when said fulcrum shifter 20 is set 120 in a position to cause the door to swing from its open toward its closed position 13.

(see Fig. 7). The free end of the dog 34 is shown as laterally and upwardly curved. The so-called hinge head 18, at one end, is provided with a tripping cam surface 39, and at its other end with a tripping cam surface 40. In the position of the parts shown in Figs. 7 and 9, the tripping cam surface 40 engages the dog 34 and raises the same so that its lock lug 35^a is above the lock shoulder 38, and when the door reaches an extreme open position, the tripping cam surface 39 will engage the said dog and raise the same, so that this lug 35^a will be above the lock shoulder 37. In all intermediate 10 positions of the door, the dog 34 will be dropped into a position in which its lug 35^a will engage with one or the other of the said lock shoulders 37 and 38. This, as is evident, positively prevents movements of 15 the actuating rod 24 while the door is in an intermediate position. The actuating mechanism will therefore always operate to perform its intended function, to wit, to cause the door to swing from its closed to its open 20 position, or from its open to its closed position.

What I claim is:

1. The combination with a swinging door, of an actuating hinge therefor, comprising 30 a fulcrum shifter pivotally mounted at the lower hinge corner of the door, a hinge head on the door detachably fulcrumed against said fulcrum shifter at points on opposite sides of the door, means for oscillating said 35 fulcrum shifter to cause the door to swing from closed to open positions, and conversely, a latch for securing said fulcrum shifter in its extreme positions while the door is in intermediate positions, and latch trips carried by the door and operative to release the 40 latch in the extreme open and closed positions of the door.

Copies of this patent may be obtained for five cents each, by addressing the "Commissioner of Patents, Washington, D. C."

2. The combination with a swinging door, of an actuating hinge therefor, comprising 45 a fulcrum shifter pivotally mounted at the lower hinge corner of the door, a hinge head on the door detachably fulcrumed against said fulcrum shifter at points on opposite sides of the door, and means for oscillating said fulcrum shifter to cause the door to 50 swing from closed to open positions, and conversely, the door, at its hinged lower corner being notched to clear said fulcrum shifter, the said notch being substantially closed by said fulcrum shifter when the door 55 is closed.

3. The combination with a swinging door suspended from the upper corner of its hinged edge, of an actuating hinge at the lower corner of the hinged edge of said door, 60 said lower hinge comprising a pivoted fulcrum shifter provided with fulcrum pin seats on opposite sides of the door, a hinge head on the door having depending fulcrum pins detachably seated against the respective 65 fulcrum seats of said shifter, and both pressed into engagement when the door is closed, an actuating rod connected to said fulcrum shifter and provided with longitudinally spaced lock shoulders, and a lock 70 dog engageable with one or the other of said lock shoulders of said actuating rod when the door is in intermediate positions, the said hinge head on the door having tripping surfaces operative on said lock dog to 75 release the same when the door is in extreme open or closed positions.

In testimony whereof I affix my signature in presence of two witnesses.

LYMAN O. HIGLEY.
